UNITED STATES PATENT OFFICE.

HARDY F. NEAL, OF DALLAS, TEXAS.

SELF-OPERATING BASEBALL GAME.

Application filed March 18, 1925. Serial No. 16,495.

To all whom it may concern:

Be it known that I, HARDY F. NEAL, a citizen of the United States, residing at Dallas, in the county of Dallas and State of Texas, have invented certain new and useful Improvements in Self-Operating Baseball Games, of which the following is a specification.

This invention appertains to game apparatus and more particularly to that type of game in which base balls are delivered to an automatic throwing device, which pitches the balls toward a person, or batsman over a plate who in turn endeavors to bat the same toward a playing field inside said base ball court having different counting or scoring sections thereon.

The primary object of the present invention is to generally simplify the apparatus, so that the same will be portable in its nature and easy to set up either outdoors such as at carnivals, parks and the like or indoors in permanent or semi-permanent amusement places without the changing of floor or ground plans, the apparatus being positioned directly on the floor or ground.

Another object of the invention is to provide a novel base ball game utilizing the standard or regulation base balls, which is positive in its operation and in which the base balls will be delivered in proper timed relation to the pitching device.

A further object of the invention is the provision of a novel arrangement of troughs and a novel arrangement of conveyor belts for rolling the balls along the troughs to the pitching apparatus, novel means being also provided for permitting the adjustment of the conveyor belts to take up slack therein caused by climate changes and the like and to position the same relative to the troughs, whereby the hanging of the balls in the troughs is eliminated.

A further object of this invention is to provide a novel court or playing field for use in connection with the game, the field having different zones marked thereon constituting different counting or scoring sections, and the representation of a base ball diamond with the players positioned stamped thereon and suitably marked to create and stimulate interest in the game.

A further object of the invention is the provision of a base ball game embodying an inclined floor and playing field or court arranged at an angle to and at one end of the floor, a trough being arranged in a novel manner for receiving the balls thrown from the court and floor, the floor also having novel means for directing the balls toward the central portion of the trough to facilitate the quick feeding of the balls to the throwing mechanism. 55

A further object of this invention is the provision of a raised platform for the batters arranged at one end of the floor in such a manner that the possibility of balls rebounding back from the curtain and getting under the batter's feet is reduced to a minimum, a novel curtain being arranged transversely of the platform so as to permit two or more batters to play the game at one time without the possibility of injuring one another. 65

A further object of the invention is the provision of an improved means for delivering the base balls to the batters which embodies an operating shaft arranged in rear of the court having associated therewith throwing arms at each end thereof arranged at diametrically opposed points whereby the apparatus will be balanced so as to operate without jar and so that the ball will be delivered first to one batter and then to the other thereby precluding the likelihood of 70 injury to either batter. 75

A further object of the invention is the provision of an improved positively operated throwing arm and a novel latch and release therefor, means being provided for permitting the adjustment of the arm, whereby different kinds of balls can be thrown in an accurate path over plate each time where the batter stands and strikes or bats the ball into scoring field in court. 90

A further object of the invention is the provision of a novel drive mechanism for the conveyor belts and novel means for adjustably mounting said mechanism in position whereby the mechanism can be accurately adjusted. 95

A further object of the invention is the provision of novel means for directing the balls from the conveyors to oppositely ex-

tending chutes toward the throwing arms, said means operating to direct first one ball in one chute and the next in the other chute and vice versa.

5 A further object of the invention is the provision of novel means for releasing one ball at a time from the chutes to the throwing arms and a novel mechanism for operating said means.

10 A further object of the invention is the provision of a novel hinge guide and brace for the releasing trigger of a throwing arm whereby the trigger will be always held in correct position, means being also provided 15 for accurately adjusting said trigger.

A still further object of the invention is to provide an improved base ball machine, court and game of the above character, which will be durable, reliable and efficient 20 in use, one that will be simple and easy to manufacture and operate and one which can be placed upon the market at a reasonable cost combined with greatest earning capacity with lowest operating expense for owner operating same.

With these and other objects in view, the invention consists in the novel construction, arrangement and formation of parts, as will be hereinafter more specifically described, 30 claimed, and illustrated in the accompanying drawings, in which drawings:

Figure 1 is a plan view of the complete game apparatus,

Figure 2 is a longitudinal section through 35 the same,

Figure 3 is a fragmentary plan view of the operating mechanism illustrating the conveyors for delivering the base ball to the guide chutes and throwing mechanism,

40 Figure 4 is a rear elevation of the operating mechanism,

Figure 5 is a side elevation of the operating mechanism illustrating the throwing arm and associate mechanism,

45 Figure 6 is a detail sectional view through one of the drive and guide wheels for the conveyor belt,

Figure 7 is a detail perspective view illustrating the novel gate for directing the passage of the base balls to first one chute and then the other,

50 Figure 8 is a detail perspective view illustrating the releasing trigger for the throwing arm and the novel guide therefor,

55 Figure 9 is a fragmentary plan view of the trigger carrying beam showing the releasing cam carried thereby,

Figure 10 is a detail perspective view of the novel base ball lifting mechanism for delivering one ball at a time to a throwing arm 60 and illustrating the novel guide therefor.

Figure 11 is a fragmentary side elevation of the frame for the conveyors and troughs illustrating the adjustability thereof,

Figure 12 is a side elevation of one of the

throwing arms showing the novel base ball receiving pocket or hand carried thereby,

Figure 13 is a front elevation of the same,

70 Figure 14 is a longitudinal section through one of the novel drums carried by the operating shaft and the novel means of associating the throwing arms therewith,

Figure 15 is a fragmentary plan view illustrating the novel arrangement of the troughs and conveyors for the base balls. 75

Figure 16 is a detail perspective view of a support for one of the guide wheels for the conveyor belt,

80 Figure 17 is a detail perspective view illustrating the mounting of the control bar for the base ball gate,

Figure 18 is a detail side elevation illustrating the connection between the control bar and one of the pivoted guide chute sections for the base ball,

85 Figure 19 is an end elevation of one of the operating drums showing the inner face thereof and illustrating the adjustable trip arm carried thereby for operating the base ball lift mechanism for delivering one ball at a time to the throwing arm,

Figure 20 is an elevation showing the opposite face of the drum,

90 Figure 21 is a plan view of the novel base and support for the drive shafts of the conveyor belt illustrating the adjustability thereof,

Figure 22 is an end elevation of the same.

95 Referring to the drawings in detail wherein similar reference characters designate corresponding parts throughout the several views, the letter A generally indicates the improved base ball game which includes a suitable frame work 25 preferably built in sections which can be readily laid upon a floor of a building without any change thereto or directly upon the ground in cases where the device is being used at parks, carnivals and the like. This frame

100 work 25 supports a flooring 26 which gradually inclines downwardly toward the rear end of the apparatus and toward the base ball court or playing field 27 which is also arranged at an incline to the vertical. This court or playing field 27 can be supported in any desired way and forms an important 110 part of the present invention and is preferably constructed from flexible material, such as heavy canvas or the like. The front face of the playing field 27 is marked by longitudinally extending lines 28 into zones 115

29 which are marked "Home run counts four points," "Third base counts three points," "Second base counts two points" and "First base counts one point." Also the representation of a base ball diamond 30 is placed upon the field in order to stimulate interest in the game and in order to add further attractiveness thereto the players positions 125 can be also marked therein with the names 130

of famous players such as Walter Johnson and the like. If preferred the names of the players on a base ball team of the locality in which the device is placed can be used.

5 A raised platform 31 is arranged at the front end of the inclined floor 26 and this floor forms a convenient plate for the batsman to stand during his attempts to bat the ball onto the playing field. All possibility of balls rebounding from the playing field under the batsman's feet is eliminated due to the raised platform 31 and I lay particular stress on this feature. The means, which is generally indicated by the 10 reference character B for throwing the balls toward the batsman is arranged directly in rear of the playing field 27 and the field is provided with suitable openings 32 through which the balls are projected. The mechanism B is so constructed as to deliver one ball at a time to the batsman and two or more batsmen can play the game at one time. The platform 31 is preferably divided by a partition 33 formed of heavy 15 netting or the like, so as to form a pair of batting boxes which will prevent the interference of one batsman with the other.

The entire game can be incorporated within a suitable enclosure suitably treated to 20 add to the attractiveness thereof and as shown side walls 34 are provided and a top wall 35 which can be provided with a sky light 36 adjacent to the field 27 so as to insure the correct lighting thereof during the 25 day time. At night time suitable electric lamps and reflectors can be advantageously arranged for illuminating the field and entire court.

At the front of the device portable steps 30 37 are provided for permitting easy access to be had to the platform 31 and these steps are arranged adjacent to the partition 33 so that persons can easily step into either one of the batting boxes.

45 Directly in rear of each batting box is arranged a score keeper's stand 38 on which is disposed a score keeper's card of novel construction (not shown). Suitable netting is arranged at the front of the device but 50 in front of the score keeper's tables or stands 38.

Arranged transversely of the floor 26 at the rear end thereof is disposed a trough 39 into which the balls are adapted to fall 55 after the same have been hit by the batsman. It is to be noted that the lower edge of the court or playing field 27 extends below the top face of the floor and is secured to the rear wall of the trough 39. This prevents the balls from hopping out of the trough when the same roll down the playing field.

A suitable conveyor generally indicated by the reference character C forming a part 60 of the operating mechanism is arranged in

the trough and carries the balls toward the transverse center of the trough in rear of the playing field to the throwing arms of the operating mechanism, as will be herein-after more fully described.

70

As much depends upon the rapidity with which the balls are delivered to the batsman the whole device is constructed to facilitate the delivering of the balls to the throwing arms and the quick operation of 75 the arms. In order to direct the balls to the central portion of the trough 39 to save loss of time in returning balls to the machine, the inclined floor 26 at the longitudinal edges thereof support inwardly directed rearwardly inclined guide cleats 40 and balls which rebound on the floor will roll down the same and strike the cleats and move toward the transverse center of the troughs.

80

A suitable frame work of two by two indicated by reference character 41 is extended from the frame work 25 rearwardly of the playing field 27 and a floor can be laid upon this frame work 41 to support the transverse trough 39.

85

The transverse trough 39 is preferably divided in sections to facilitate the carrying and transporting thereof and includes a pair of independent portions 42 which terminate in rearwardly directing arcuate guides 43 95 at the transverse center of the trough. Communicating with the arcuate guides 43 of the portions 42 are upwardly inclined downwardly directing troughs 44 and 45 which lead into the rearwardly inclined chamber 100 46 having the elongated swinging gate 47 arranged therein for directing the balls to the oppositely directed laterally extending downwardly inclined guide chutes 48 and 49, clearly shown in Figure 4 of the drawings. It is to be noted at this point that the laterally directed chutes 48 and 49 are connected to arcuate guide troughs 50 and 51 respectively which communicate with the extreme rear end of the chamber 46. In 105 order to insure the proper alining of the arcuate guide sections 50 and 51 with the chamber 46 the same carries rearwardly extending tongues 52 on which the forward terminals of guide sections are adapted to 110 rest.

110

A novel supporting frame work is provided for the troughs 39, 44 and 45, so that the troughs can be easily set up and adjusted to the character of the ground on 115 which the game is placed. This frame work also provides means whereby the pulleys and guide wheels for the conveyor belts 53 and 54 can be adjusted relative to the trough and to permit slack to be taken up 120 in the belt caused by climate changes. As shown corner guide wheels or pulleys 55 and 56 are arranged at the terminals of the trough portions 42 and these pulleys are 125 keyed or otherwise secured to suitable sup- 130

porting shafts 57 rotatably mounted in thrust bearings 58. The thrust bearings 58 are formed on or carried by base plates 59 secured in any preferred manner to beams 5 or supports 60 which are in turn adjustably connected by means of connecting plates 61 with longitudinally extending beams 62.

The frame work also includes inclined struts 63 upon which are arranged the 10 troughs 44 and 45. As clearly shown these struts 63 are arranged in sections and the sections are connected together by a brace plate 64 suitably slotted for the reception of connecting bolts 55. This permits the 15 lengthening or shortening of the struts. It is to be also noted that the inner guide pulleys 56 are adjustable on the struts through the medium of suitable bolts 65 operating through slots 66 of the base plates for the 20 support of said pulleys. Similar guide and drive pulleys 67 are arranged at the inner ends of the troughs 45 and 46 and these drive pulley wheels are disposed intermediate the troughs 44 and 45 and the chamber 25 46. Intermediate pulley and drive wheels 68 are disposed on each side of the troughs 44 and 45 between the ends of the pulley wheels 55 and 67. These pulley wheels 68 are adjustably mounted on suitable supports 30 69 so as to permit the pulley wheels to be moved toward and away from the runs of the pulley belts 53 and 54 to take up slack therein.

The pulley belts 53 and 54 are trained 35 about the pulleys 55, 56, 67 and 68 in a manner clearly shown in Figures 3 and 15 of the drawings and these belts are so constructed as to roll the balls along the troughs so as to materially reduce friction 40 and to prevent the balls from being dragged through the troughs. Each of the belts have secured thereto at equidistant spaced points suitable triangular shaped flights 70 for engaging the said base balls.

45 All of the drive and guide pulley wheels are constructed substantially the same and each include a hub 71 and disk shaped end plates 72 which extend beyond the periphery of the hub. In order to prevent slipping of the belt, the periphery of each hub is provided with transversely extending drive cleats 73 for engaging the said conveyor belt.

As heretobefore stated the operating 55 means B is arranged below the playing field 27 and embodies a bed 75 which is also portable in nature and which can be fitted directly upon the ground or floor of a building. This frame 75 supports a transversely 60 extending drive shaft 76 the forward end of which has keyed or otherwise secured thereto a drive pulley wheel 77, which can be driven from any preferred type of prime mover such as an electric motor (not 65 shown). The shaft is preferably mounted

in suitable roller bearings 78, which bearings are adjustably supported as at 79 by hangers 80. This shaft 76 has keyed or otherwise secured thereto a worm 81, which meshes with a worm wheel 82 carried by a 70 longitudinally extending driven shaft 83 which forms means for operating the conveyor belts 53 and 54. I have provided a novel drive for these belts in order to prevent slipping thereof and to insure the 75 quick, positive operation of the belt, whereby a maximum quantity of balls will be delivered to the throwing mechanism. This drive means embodies intermeshing spiral gears 84 and 85 adjustably keyed respectively to the shaft 83 and to inclined shafts 86 which support the drive pulley wheels 67. The shaft 83 is also preferably mounted in balls or roller bearings which are fitted in adjustable hangers 87 carried by the 80 frame 75. The shafts 86 are also mounted in a novel manner so that the same can be readily adjusted to permit the proper engagement of the gears 85 with the gears 84 and the proper operation of the conveyor 90 belts. As shown the shafts 86 adjacent to their upper terminals are mounted in bearings 87 carried by a transversely extending plate 88 which is connected by means of screws 89 to a suitable base plate 90 carried 95 by the frame 76. These screws 89 are fitted in suitable slots formed in the plate 88, whereby adjustment of said plate can be readily had. The lower terminals of the shafts 86 are mounted within suitable thrust 100 bearings 91 which have formed thereon suitable base plates 92 which are fitted upon an incline supporting plate 93. This plate 93 is securely bolted as at 94 to a suitable part of the supporting frame work or bed 76. In 105 order to permit the expeditious adjustment of the thrust bearings 91, so that the desired angular adjustment of the shaft 86 can be had, the supporting plate 93 is provided with longitudinally extending 110 slots 95 through which are adapted to extend adjusting bolts or screws 96. These bolts or screws, pass through slots 97 formed in the base plate 92. As clearly shown in Figure 21 of the drawings the slots 97 extend at 115 right angles to the slots 95 which permit the adjustment of the thrust bearings longitudinally and transversely of the plate 93.

Arranged in rear of the shaft 83 and in parallel relation thereto is the operating 120 shaft 100 utilized for actuating the base ball throwing mechanism. This shaft 100 is mounted in suitable bearings 101 carried by supporting standards 102 which are firmly secured to the bed 75. I prefer to provide 125 inclined braces 103 for the standards 102 in order to prevent rocking or back lashing movement thereof.

Keyed or otherwise secured to each end of the shaft 100 is a novel ball throwing mech- 130

anism 104 which will be described in detail. It is to be noted at this point that the shaft 100 is driven at a constant speed from the drive shaft 76 through the medium of a 5 suitable worm and worm wheel 105 and 106 adjustably keyed respectively to the shafts 76 and 100. The ball throwing devices 104 are arranged in front of and at the terminals of the chutes 48 and 49 and in order to 10 convey the balls to said throwing devices chutes 107 are provided which extend downwardly and forwardly toward the front of the machine.

Each of the ball throwing devices 104 embodies a drum 108 which includes an annular rim 109, an end plate 110 and a hub 111 carried thereby which is keyed or otherwise secured to the shaft 100. Arranged within the rim 109 and secured thereto is 15 a bed block 112 to which is secured a door check and closure 113 preferably of the Yale type. This door closure is of the conventional construction and has therefore not been shown in detail and it is sufficient to 20 state, that the same includes a shaft 114, which when turned in one direction places a suitable control spring therein under tension and which, when released rapidly rotates the shaft a predetermined distance and 25 then gradually checks the rotation thereof. This mechanism is utilized for throwing the ball and a throwing arm 115 is keyed to the said shaft 114 and takes the place of the usual door closing arm. This arm 115 has 30 the outer end thereof provided with a cup or hand 116 for receiving the base ball and this cup or hand scoops the ball from the forwardly inclined guide chutes 107. The hands 116 are shown in detail in Figures 35 12 and 13 and the same forms an important part of the present invention. Each hand or scoop embodies a yoke 117 adjustably carried by the arm 115. The terminals of 40 the yoke support a semi-circular strap 118 arranged at right angles thereto and the central portion of this strap has secured thereto a semi-circular strap 119. The forward terminals of the strap 118 have riveted or otherwise secured thereto an open annular band 120 which can be rocked on the 45 strap 118 through the medium of a suitable adjusting bolt 121 which is connected respectively to the inner ends of the band 120 and the strap 119. The adjustment of the 50 band 120 and the strap 119 forms means for controlling the character of the ball pitched. In order to balance the arm 115 a suitable ball weight 123 is connected to the 55 inner end thereof, as clearly shown in Figure 14 of the drawings. This weight can be adjustable if desired.

In order to balance the whole machine and to effectively reduce vibration the arms 115 at the opposite ends of the shaft 100 are

arranged at diametric disposed points on the 65 shaft, so that the base balls will be alternately thrown first from one side and then the other. As stated this also gives the batsman an opportunity to bat the balls without 70 interference with one another.

I have provided a novel releasing mechanism for the throwing arm and this mechanism embodies a trigger 125 which is adjustably carried by socket 126. This socket 126 is also adjustable longitudinally of a 75 supporting beam 127 as can be clearly seen in Figure 8 of the drawings. This beam 127 extends transversely of the bed 75 and is hingedly connected as at 128 to a suitable portion of the bed. I also prefer to make 80 the hinge adjustable in a vertical plane whereby the height of the beam can be accurately set relative to the other operating parts of the mechanism. This trigger 125 is normally arranged in the path of the 85 throwing arm and during the rotation of the drum holds the arm against movement for a predetermined length of time until the spring in the door check 113 has been placed 90 under the desired tension at which time the trigger is moved out of the path of the arm so as to permit the arm to swing rapidly 95 in arcuate paths for throwing the base ball through the aperture 32 in the playing field over the plate. The trigger is moved from 100 out of the path of the arm by the use of a trip arm 129 carried by the periphery of the rim 109 of the drum. Arranged in the path of the trip arm 129 is a cam 130 carried by the beam 127 and it is obvious that when the trip arm strikes the cam 130 that the beam 127 will be swung inwardly and the trigger out of the path of the arm.

It is necessary to provide a suitable guide and brace for the trigger in view of the 105 force placed on the trigger by the arms 115. As shown a sleeve 131 slidably receives the trigger and this sleeve can be rockably carried by the upper end of a frame 132 which is preferably formed of pipe firmly bolted 110 and otherwise secured to the bed. The sleeve is further braced and adjustably connected with the bed by turn buckle structure 133 which also allows an accurate adjustment of the trigger to be had relative to the throwing arms. The trigger and the beam 127 is normally held in a predetermined position by contractile coil springs 134 which has the terminals connecting respectively to the 115 guide sleeve 131 and a take up bolt 135 connected with the beam 127. By adjusting the take up bolt 135, the tension of the spring 120 can be regulated.

It is preferred to feed first one ball to one chute 48 or 49 and then the next ball to the 125 other chute, and as heretofore stated the gate 47 is provided for this purpose. The gate 47 has its inner end secured to an L-

shaped lever 136 which is rockably carried by the chamber 46 in such a manner that one arm of the lever is disposed below the chamber and parallel with the bottom wall thereof. The mechanism for operating the gate 47 includes a yoke 137 carried by a forwardly extending arm 138 formed on a rock bar 139. This rock bar 139 is rockably mounted directly in rear of the arm 138 on a pivot pin 140 carried by the upper end of a suitable standard 141. This pin 140 can be adjusted in a vertical plane so that the height of the lock bar 139 can be regulated. The opposite terminals of the rock bar 139 are pivotally connected as at 141 to the lower terminals of depending arms 142, the upper terminals of which are adjustably connected by the means of yokes 143 to the chutes 49. The outer lower ends of these chutes 48 and 49 are rockably connected by means of pins 144 with uprights 145 carried by the bed 75. It is to be noted that the chutes 48 and 59 can be adjusted on the posts or standards 145 both in a vertical and in a horizontal plane, and that these posts extend above the V-shaped bottoms of the chutes to form stops for the base ball. As shown the opposite sides of the standards or posts 145 at the upper ends thereof are beveled to facilitate the passage of the base ball thereover, when the same are lifted by the mechanism 147 which will be hereinafter more fully described. The inner end of the chutes 48 and 49 are connected by means of fastening elements 148 with the arcuate guides 50 and 51 so that these guides will swing with the chutes and as stated the fingers 52 permit the proper alining of the arcuate guides with the chamber 46. Referring to Figure 4 of the drawings, it can be seen that when a base ball rolls on to the guide 50 and chute 48 that the same will rock on the pivot pin 144 causing the rocking of the bar 139 and the moving of the gate 47 to the opposite side of the chamber whereby the next ball will be guided into the guide 51 and chute 49 whereupon the gate will be moved in the opposite direction.

The means 147 for lifting the balls one at a time over the post 145 includes a lift arm 148 having a beveled upper end 149 on which a ball is adapted to seat. This lift arm is adapted to operate through a suitable slot in the chute adjacent to the post and an adjustable guide strap 150 is carried by the post for the said lift arm. The lift arm is secured to the inner end of an elongated beam 151 which is hingedly connected at its forward end as at 152 to a suitable portion of the bed. This hinge can also be adjustably carried by the bed in order that the height of the beam can be accurately set. A trip arm 153 is carried by the beam 151

and is provided with an arcuate upper end 154 normally arranged in the path of a lift pin 155 adjustably carried by the end plate 110 of the drum 104. This lift pin 155 is arranged in a predetermined relation relative to the throwing arm 115 and the trip pan 129 and it is obvious that when the lift pin 155 strikes the curved upper terminal 154 of arm 153 that the lift arm 148 will be raised so as to move a single ball over the adjacent standard or post 145 into the forwardly extending guide chute 107 and into the pocket or hand 116 of the throwing arm. To prevent movement of a base ball adjacent to the ball being lifted a transversely extending stop strap 156 is carried by the trough as clearly shown in Figures 3 and 4 of the drawings.

Suitable automatic shutters (not shown) are provided for the ball openings in the ball playing field 27.

In the operation of the improved device the base balls will be collected in the trough 39 and carried into the chamber 46 where the same will be directed by the gate 47 first into one trough 48 and then into the other. The balls will now be fed one at a time, by the lift arm into the guide chutes and into the cups or hands 116 where the same will be thrown through the playing field by the arms 115 upon the release of the same by the triggers 125 as heretofore explained. As the balls are pitched over the plate toward the batsman the same are struck or batted toward the playing or scoring field and wherever the ball first hits or strikes, the same counts a predetermined number of points and the score of a particular batsman is kept on the score sheet. Owing to the nature of the ball or playing field 27 the game is practically self-explanatory and creates a maximum amount of amusement for the users thereof.

Changes in details may be made without departing from the spirit or the scope of this invention, but:

What I claim as new is:

1. In a game apparatus including a bed, a pair of spaced parallel shafts carried by the bed, a common operating shaft for said first mentioned shafts, a chamber located above said shaft, conveyors leading to said chamber, guide chutes leading toward the terminals of one of said first mentioned shafts, ball throwing devices carried by the terminals of the mentioned shaft and means for operating the conveyors from the other shaft of said first mentioned pair of shafts.

2. In a game apparatus, a bed, a transversely extending operating shaft mounted upon the bed, a longitudinally extending shaft arranged adjacent to the front of the bed and driven from said operating shaft, a second shaft arranged longitudinally of the

- bed and in spaced parallel relation to the first longitudinally extending shaft, means for operating the second longitudinally extending shaft from the operating shaft, ball throwing devices operated by said second mentioned shaft, a chamber arranged above said shafts, conveyors for directing balls into said chamber, guide chutes extending from the chamber to said ball throwing devices, inclined operating shafts for said conveyors arranged adjacent to said first mentioned longitudinally extending shaft, and spiral gears operatively connected to the inclined operating shaft with said first mentioned longitudinally extending shaft.
3. In a game apparatus, a bed, a drive shaft arranged transversely of the bed, a longitudinally extending shaft disposed adjacent to the front of the bed and operated from said drive shaft, a second longitudinally extending shaft carried by the bed and operated from said drive shaft and disposed in rear of the first longitudinally extending shaft, a ball receiving chamber arranged above the shaft, ball throwing devices carried by the terminals of the second mentioned shaft, guide chutes leading from said chamber to said ball throwing devices, conveyors leading to said chambers, adjustable inclined shafts for operating said conveyors and intermeshing spiral gears carried by the first mentioned longitudinally extending shaft and said operating shaft.
4. In a game apparatus, a bed, a transversely extending drive shaft carried by the bed, adjustable hangers for said drive shaft, a base ball receiving pan arranged above the drive shaft, conveyors for feeding balls to the chamber, an adjustable inclined plate arranged above the drive shaft, bearings connected with said plate, an adjustable base plate carried by the bed, thrust bearings movable longitudinally and transversely of the base plate, inclined operating shaft for the conveyors mounted in said bearings, a longitudinally extending shaft operatively connected to the drive shaft, spiral gears connecting the longitudinal shaft with the operating shafts, a second longitudinally extending shaft, ball throwing devices carried by the terminals of the last mentioned shaft, and means for guiding the balls from the chamber to said ball throwing devices.
5. In a game apparatus, an inclined floor, an inclined playing field arranged at one end of the floor and extending below the floor, a transversely extending trough connected respectively to the floor and the playing field, inclined troughs communicating with the first mentioned troughs and leading in rear of said playing field, a chamber communicating with the inclined trough, ball throwing devices disposed in rear of the playing field on each side of the chamber, means for directing one ball at a time to the ball throwing devices, and conveyor belts arranged in said trough each including triangular shaped plates for engaging and rolling balls along the troughs, and means for operating said belt including adjustable guide and drive pulleys, inclined operating shafts for certain of said pulleys, a drive shaft, an operating shaft driven from said drive shaft, and spiral gears operatively connecting the operating shaft with said inclined shafts.
6. In a game apparatus, a bed, a chamber arranged above the bed, ball throwing devices arranged on each side of the chamber, means for feeding balls to the chamber, laterally extending guide chutes communicating with the rear end of the chamber and extending from the opposite side thereof, forwardly extending guide chutes communicating with the outer terminals of a laterally extending guide chute and terminating adjacent to said ball throwing devices, means rockably connecting the outer terminals of the laterally extending chutes to the bed, an elongated gate arranged in the longitudinal center of the chamber for movement from one side thereof to the other for controlling the movement of the balls to first one chute and then the other, an L-shaped lever movable with said gate, a rock bar mounted for movement at a point intermediate its ends, means connecting the terminals of a rock bar to the laterally extending guide chutes and a forwardly extending arm connected with the central portion of the rock bar, and operatively connected to said L-shaped lever for causing movement of said gate upon movement of said laterally extending chute.
7. In a game apparatus, a bed, a pan for receiving base balls arranged above the bed, ball throwing devices arranged on each side of the pan, means for operating said ball throwing devices alternately, means for feeding base balls to said pan, laterally extending guide chutes communicating with the rear end of the pan and extending from opposite sides thereof and automatically operating the gate disposed in the pan for guiding balls first into one chute and then into the other, a stop disposed at the outer end of each chute, forwardly extending guide chutes arranged below the stops and leading to said ball throwing devices, and a lift arm movable through the laterally extending chutes and slidably associated with said stop for moving the balls one at a time over said stop and into said forwardly extending guide chutes, and means actuated from said ball throwing devices for operating said lift arm.
8. In a game apparatus, a bed, a pan for receiving base balls arranged above the bed,

ball throwing devices arranged on side of the pan, means for rotating said ball throwing devices alternately, means for feeding base balls to said pan, laterally extending 5 guide chutes communicating with the rear end of the pan and extending from opposite sides thereof, a stop disposed at the outer end of each chute having the opposite faces thereof beveled, forwardly extending guide 10 chutes arranged below the stops and leading to said ball throwing devices, a lift arm movable through the laterally extending chutes and slidably associated with said stop for moving the balls one at a time over 15 said stops, the upper face of said lift arm being inclined for engaging a ball, a rearwardly extending beam, means hingedly connecting the forward ends of the beam with the bed, means connecting the rear end 20 of the lift arm with the beam, an adjustable lift arm connected with the beam having an arcuate upper terminal, and an adjustable lift pin carried by said ball throwing devices for engaging the arcuate terminals of 25 said adjustable lift arm.

9. In a game apparatus, a bed, a pan arranged above the bed at the central portion thereof, conveyors for introducing base balls into the pan, base ball throwing devices arranged on opposite sides of the pan, 30 means communicating with the rear end of the pan for leading the balls one at a time alternately to said ball throwing devices, each of said ball throwing devices including 35 a throwing arm and a radially extending trip pin, a beam movable in a horizontal plane, a trigger carried by the beam normally disposed in the path of the throwing arm for holding the same against movement, 40 a pan carried by the beam and disposed in the path of said trip pin whereby upon engagement of the pin with said pan the trigger will be moved out of the path of the throwing arm, a guide and a brace for said 45 trigger including a rigid frame carried by the bed, a guide sleeve receiving the trigger connected with the frame, means resiliently connecting the beam and guide sleeves together, and an adjustable take up connecting 50 the guide sleeves to said bed.

10. In a game apparatus, a baseball receiving pan, a supporting bed, means for delivering base balls to the pan, laterally extending guide chutes connected with the rear end of the pan and extending in the opposite sides thereof, ball throwing devices disposed on each side of the pan for receiving balls from said guide chutes, each of said ball throwing devices including a 55 spring operated throwing arm, means for tensioning the spring, a trigger arranged in the path of the arm to normally hold the same against movement, a beam hingedly connected with the bed for swinging move- 60

ment in a horizontal plane, means for adjusting said beam, means adjustably connecting the trigger with the beam at a point remote from the pivot point thereof, and a trip pin adjustably carried by said ball throwing devices, and a cam connected with 65 said beam and disposed in the path of the trip pin, and a guide and brace for said trigger including a rigid frame carried by the bed, a sleeve carried by the frame slidably receiving the trigger, a contractile coil 70 spring normally holding the trigger in the path of the throwing arm connected respectively to the guide and said beam, and means for tensioning said spring.

11. In a game apparatus, a bed, a shaft 80 extending longitudinally of the bed, means for operating the shaft, a pan arranged above the shaft, conveyors for introducing base balls into the pan, base ball throwing devices associated with each end of the shaft, 85 means for guiding the base balls alternately and one at a time from the pan to said ball throwing devices, each of said ball throwing devices including a drum keyed to the shaft, a door closure and check disposed within the drum and including a rotatably spring operated shaft, and a ball throwing arm connected with said shaft of the door closure, means for counter balancing the arms, and a bearing bracket connected with the drum receiving the terminal of the said shaft, a trigger for normally holding the arm against movement during rotation of the drum, a ball receiving cup carried by the outer end of said arm and means for releasing the trigger 95 from said drum.

12. In a game apparatus, a bed, a longitudinally extending shaft carried by the bed, means for operating the shaft, a pan arranged above the shaft, conveyors for feeding base balls to the pan, base ball throwing devices carried by the terminals of the shaft and arranged on each side of the pan, guide chutes extending from the rear end of the pan to said ball throwing devices, a stop at each chute, a ball raising device adjacent each stop for moving balls one at a time over said stop, each of said ball throwing devices including a drum keyed to the shaft for rotation therewith, a door check and closure mechanism carried by the drum including a spring operated shaft, a throwing arm connected with the shaft, the throwing arms of the ball throwing devices being disposed in diametric relation relative to one another, means for counter-balancing said arms, a trigger for normally holding the arms against movement, and an adjustable trip carried by the drum for operating said trigger, and an adjustable lift pin carried by the drum for operating said ball lifting device.

13. In a ball throwing device, a throwing

arm, a ball receiving cup carried by said arm including a yoke adjustably connected with the arm and a semi-circular strap connected to the terminals of the yoke and arranged at right angles thereto, a second semi-circular strap arranged in rear of the yoke and connected to the first mentioned

strap, an open annular band secured to the terminals of the first mentioned strap in front of said yoke, and means, for adjustably connecting the last mentioned strap and band together. 10

In testimony whereof I affix my signature.
HARDY F. NEAL.
